Des. 185,462
Patented June 9, 1959

185,462

SHOE SOLE

Edward Ratner, Manhattan, N.Y.

Application December 12, 1958, Serial No. 53,739

Term of patent 14 years

(Cl. D7—5)

Fig. 1 is a bottom perspective view of a shoe sole showing my new design;

Fig. 2 is a bottom view of said sole; and

Figs. 3 and 4 are sectional views taken substantially along the lines 3—3 and 4—4 respectively of Fig. 2, the same illustrating details of the design that cannot be seen in a side view.

I claim:

The ornamental design for a shoe sole, substantially as shown.
